WINDOW SCREEN

Harry A. Kammerer, Mount Vernon, N. Y.

Application April 25, 1935, Serial No. 18,243

4 Claims. (Cl. 156—14)

The present invention relates to window screens and has for its object to provide a simple form of screen which can be readily secured in position under proper tension and when removed 5 may be rolled up compactly about the frame members for safe storage.

A further object is to provide an improved frame member combining therein a face plate and a rearwardly extending flange, the said face plate having bearing surfaces above and below the flange with means to secure one edge of the screen fabric to the inner face of one of said bearing surfaces with the other bearing surface in position to make contact with the outer sash 15 guide of the window frame, with the inwardly extending flange in position to be engaged by the locking devices to hold the frame member with the screen thereto attached in proper position.

A further object is to so construct the frame member that it may be employed if desired in forming a rectangular screen frame having appropriately mortised joints and to make it possible to cut a frame member on an angular line so as to match the angular end of an adjacent 25 frame member without the necessity of reversing the material so as to produce reversed angular ends on the same frame member.

A further object is to provide a simple mechanical connection, union or joint, between the 30 angular ends of adjacent frame members in the formation of a rectangular frame.

Other objects will appear in connection with the following description of the invention.

The invention is illustrated in the accompanying 35 drawing in which—

Fig. 1 shows a broken vertical cross-sectional view on the line 1—1 in Fig. 2, extending through a window frame with one form of the window screen in position therein;

Fig. 2 shows a broken view of a window frame with the screen shown in Fig. 1 in position showing the inner face thereof;

Fig. 3 is a fragmentary detail, a portion of the window frame being shown in section on the line 3—3 in Fig. 4, and showing a plan view of the inwardly projecting flange and one of the tension-applying locking devices therefor;

Fig. 4 is a fragmentary view partially in section taken on the line 4—4 in Fig. 3 and at right angles to Fig. 3;

Fig. 5 is a fragmentary perspective view showing a portion of one of the frame members secured to one end of the screen material;

Fig. 6 is a fragmentary view showing the rear 55 face of a corner of a rectangular screen frame

with the screen material connected to the adjacent frame members, the angular ends of which have been secured together and comprising a screen with a rectangular frame.

Similar reference characters will be employed 5 to designate corresponding parts.

In the drawing 1 represents a window frame of the usual and ordinary construction supporting the usual upper sash 2 and lower sash 3. As usual in such frames, there are suitable guides 10 4 and 5 forming the guide channels 6 and 7 in which the sash members 2 and 3 are guided in their sliding movement. At the bottom there is provided the usual sill member 8.

In the form of my invention shown in Figs. 1 to 5, a strip of screen material 9 is provided at its upper and lower ends with the frame members 10. Each of the frame members 10 is made of a metal casting, preferably some light, strong, and non-tarnishable metal such as aluminum or 20 an aluminum alloy, and each frame member 10 will have a rounded front face 11 and a flat rear face 12. In the flat rear face 12 there will be formed two longitudinally extending grooves or channels 13. Centrally positioned between the 25 channels 13 there is a longitudinally extending flange 14 formed integrally with the front member of the frame 10 and positioned centrally of the channels 13, the said flange 14 being of substantial width so as to make contacts with the 30 opposed outer face of the guide members 5 at the top and bottom of the frame 1. The flanges 14, when used as shown in Figs. 1 to 5, are cut away at their opposite ends as shown at 15, leaving the front member of the frame extending laterally 35 at each end of the flange 14 in order that the inner face 12 of the members 10 at the top and bottom of the screen above and below the flange 14 may firmly bear against the outer face of the sash frame 5 at or near each end thereof, and 40 entirely contact with the outer face of the sash frame 5 at each end.

The screen material 9 is permanently connected to the inner face 12 of the member 10 by means 45 of a metallic rod 16 which is laid upon the marginal edge of the fabric and forced into the groove 13 wedging the fabric and rod into the channel 13 at one side of the flange 14. As the portion 10 of the frame member is provided with grooves 50 along both sides of the flange 14, it is obvious that a section of the frame member may be connected to either end of the screen fabric 9 without the necessity of adjusting the frame member sections as would be necessary if but a single groove 55

was formed in the inner face of the member 10.

At or near the ends, the flanges 14 are provided with openings 17 by means of which the frame members are connected to the attaching means as, for instance, threaded screws 18 at the top, the heads of which pass through the slots 17 and are engaged by latch plates 19, said latch plates being pivoted as at 20, all as shown in Figs. 1 and 2 of the drawing.

10 The frame member 5 at the bottom adjacent the sill 8 will be provided with metal plates 21 having threaded sockets 22 in which a threaded stud 23 is adjustably mounted. The threaded stud 23 at its upper end is provided with an open hook 24, constituting bearings for the latching cam levers 25, each of which is slotted at 26 to receive the upper hooked end of the stud and also carrying a pintle 27 to detachably connect the lever with the hooked end of the stud. The lever will preferably be provided with an extended end or handle 28, by means of which the cam portion of the lever 25 may be locked while in engagement with the upper surface of the flange 14, thus applying tension thereto and to the screen fabric and locking it in position, all as shown in Figs. 1, 2, 3, and 4 of the drawing.

In Fig. 6 the frame-forming metal molding or material is shown mortised at the corners, as at 29, with the screen material 9 having its ends and side edges 30 and 30' secured in the grooves at one side of the flange 14. The outer grooves 31, in this form of frame, receive an angular piece of metal 32 driven therein and spanning the joint formed by the mortise cuts whereby the frame members may be permanently united and a screen having a rectangular frame bounding and attached to the screen material along all its edges may be produced.

30 In this form of the invention, as in the form first described, the so-called metal frame "molding" along its inner surface at one side of the flange 14 will form a firm bearing for the screen material and upon the other side of the flange 14 provide a firm bearing against the sash guide 5 of the window frame 1.

35 In this form of the invention any suitable detachable fastening means, such as those shown and described, may be employed to connect the

frame of the screen in position in the window frame.

It is thought that the operation of the invention has been sufficiently disclosed in connection with the foregoing description of its 5 construction and that no further description thereof will be necessary.

I claim:

1. A window screen comprising frame members provided with a face plate and an attaching 10 flange, the latter located at the back of the face plate at right angles thereto, and said face plate provided upon its rear face with longitudinal grooves located above and below the plane of the attaching flange, and flexible screen material connected to the frame members by a clamping bar wedging the screen material into one of the longitudinal grooves.

2. A rectangular frame for window screens comprising a frame member having upon its rear 20 face a flange extending at right angles thereto, parallel grooves in the rear face, one above and one below said flange, adjacent sections of the frame being mitered to form a corner thereof, and an angular wedge bar in one of the grooves 25 at the meeting ends thereof to unite said mitered corners, and screen material having its edges secured in the other of said grooves.

3. Window screen frame material comprising a face member and a flange member formed in- 30 tegraphy, the flange member extending from one surface of the face member at right angles thereto, the rear surface of the face member having a longitudinally extending groove upon each side of the flange member.

4. A window screen comprising frame members each provided with a finished rounded face plate having a flat back, an attaching flange located at the back of the face plate and ex- 40 tending at right angles thereto, said face plate provided upon its rear flat face with a longitudinal groove adjacent the attaching flange and extending parallel therewith, flexible screen material, a clamping bar wedging the screen mate- 45 rial into said longitudinal groove, the screen being adjustably connected to the window frame at the top and bottom thereof.

35 HARRY A. KAMMERER.
